ELECTRON DISCHARGE DEVICE FOR
VERY HIGH FREQUENCIESDonald Harrison Black, London, England, assign-
or to International Standard Electric Corpora-
tion, New York, N. Y.Application August 29, 1940, Serial No. 354,657
In Great Britain September 13, 1939

3 Claims. (Cl. 250—27.5)

This invention relates to electron discharge devices of the so-called velocity modulated type. Briefly the operation of such devices is as follows:

A beam of electrons of uniform velocity is passed through a gap in a resonator to which is applied the resonant frequency. In passing across the gap, the electrons are accelerated or decelerated according to the phase of the oscillations at the time at which they pass. After leaving this resonant system, or modulator, the electrons pass through a field-free space, and while in this space a certain degree of bunching of the electrons takes place. This is due to accelerated electrons catching up on the slower ones which preceded them through the modulating gap. The bunched electrons then pass through a second resonant system which is in oscillation and the circuit is so arranged that, owing to this bunching, more electrons will be decelerated on passing through the gap than will be accelerated. If such a state of affairs exists, then the energy given up to the second resonant system by the electrons which are decelerated will exceed the energy extracted from it by those which are accelerated, the net result being a gain in energy by the resonant system.

In the known systems, a single beam of electrons is passed through resonators of various types and some difficulty is experienced in obtaining beams of the required magnitude. In the suggestions so far put forward the source of electrons is usually external to the resonators. In the arrangements now proposed, the electron source is partly or completely enclosed by the resonators and some of the difficulties encountered in the formation of beams are largely overcome.

In one aspect the invention resides in an electron discharge device of the velocity modulated type comprising two co-axial cavity resonators of annular cross-section lying one within the other and an electrode system for projecting electrons radially through grids or apertures in the resonator walls.

In another aspect the invention resides in an electron discharge device of the velocity modulated type wherein two resonant cavities of annular cross-section are defined by co-axial cylindrical surfaces, an electron source being provided along the axis of the structure for projecting electrons radially through grids or apertures in the cylindrical surfaces.

These and other further aspects of novelty and invention will hereinafter be pointed out or will become apparent from a reading of the follow-

ing specification in conjunction with the drawing included herewith. In said drawing:

Fig. 1 is a cross-sectional elevation of an electron discharge device incorporating features of the invention;

Fig. 2 is a cross-sectional view taken substantially in the plane of 2—2 in Fig. 1; and

Figs. 3 and 4 are further cross-sectional views taken transversely to the plane of Fig. 1.

Referring to Fig. 1, which is a section through the structure a cathode 1 is surrounded by a series of concentric grids 2, 3, 5, 7, 9, the axis of revolution being X—X. The grids are represented by dotted lines but in practice would probably be of squirrel cage formation, being made up from a series of rods. Fig. 2 shows a sectional view across the line 2—2 of Fig. 1. It will be noticed that the rods forming the respective grids lie on radial lines extending from the cathode. This is a preferred arrangement in order to reduce the number of electrons collected by the grids.

Grid 2 is normally operated at a negative potential with respect to the cathode and its purpose is to control the magnitude of the space current. Grids 3 and 5 form portions of cylinders 4 and 6 respectively. The spaces between the ends of the cylinders are closed by the annular discs 16 and 19. The two cylinders with their end discs thus form a resonator of the concentric line type. Similarly grids 7 and 9 form portions of the cylinders 8 and 10 which with the end discs 17 and 18 form a second concentric line resonator. Cylinders 6 and 8 are joined by two discs placed at the ends of the grid portions as shown. The cylinder 11 collects the electrons which pass through the system.

The electrons in passing from the cathode 1 to the collector 11 pass through two resonators. If the inner resonator has oscillations applied to it, the electrons will be velocity modulated as described above. While moving between the field free space between the inner and the outer cylinders, bunching of the electrons will take place and energy will be imparted to the outer resonator. Oscillations set up in the second resonator may be taken off by means of lead 12 which contacts with the cylinder 8 through a concentric tube 13. Other methods for withdrawing energy from the second resonator are possible.

If the device is to be used as an oscillator, then some of the energy from the outer resonator must be fed back to the inner resonator. One method of carrying this out is shown in Fig. 1 and in Fig. 3 which is a section across the line

3—3 in Fig. 1. An elongated loop of wire 14 has one limb in the centre of a connecting tube 15 and the other limb just outside or in the wall of 15. The rounded ends of the loop project into the inner and outer resonators. The coupling between the two resonators is varied by a lateral displacement of the loop which exposes a greater area of loop in one resonator than in the other.

The permissible distance between grids 3 and 5 and between grids 7 and 9 depends upon the speed of the electrons and the frequency of operation. The time of flight across these gaps must not exceed a certain fraction of the period of one complete oscillation. In some cases it may be found that the grids must be placed closer together than is desirable for the spacing between the cylinders if these are to form an efficient resonator. Fig. 4 shows how this may be improved by replacing the rods with strips of metal set radially. The walls of the cylinders 8 and 10 could then be placed on the inner and outer circumferences of 7 and 9 respectively.

For efficient operation of such a device the two resonators must be exactly in tune. One resonator may have a fixed frequency and the other may be tuned by sliding the end disc 19 of the inner resonator up and down.

Various methods are available for ensuring that the electron paths are in vacuum; for example the structure may be wholly enclosed or parts of the resonators may form parts of an evacuated envelope.

What is claimed is:

1. An electron discharge device including an inner pair of coaxial sheet-metal cylinders joined at their ends by annular discs, an outer pair of coaxial sheet-metal cylinders joined at their ends by annular discs, said inner and said outer pairs

being coaxial with each other, a pair of axially spaced annular discs between said inner and outer pairs of cylinders providing a substantially field-free drift space, and generally longitudinally extending grid members provided between said axially spaced annular discs in apertures in each of the walls of said cylinders.

2. An electron discharge device including an inner pair of coaxial sheet-metal cylinders joined at their ends by annular discs, an outer pair of coaxial sheet-metal cylinders joined at their ends by annular discs, said inner and said outer pairs being coaxial with each other, a pair of axially spaced annular discs between said inner and outer pairs of cylinders providing a substantially field-free drift space, generally longitudinally extending grid members provided between said axially spaced annular discs in apertures in each of the walls of said cylinders, a connecting tube between said cylinders, and a loop of wire projecting through said tube into the two cylinders.

3. An electron discharge device including a cathode, a grid surrounding said cathode, an inner pair of coaxial sheet-metal cylinders surrounding said grid and joined at their ends by annular discs, an outer pair of coaxial sheet-metal cylinders joined at their ends by annular discs, said inner and said outer pairs being coaxial with each other, a pair of axially spaced annular discs between said inner and outer pairs of cylinders intermeshing at the ends of the cylinders and providing a substantially field-free drift space, and generally longitudinally extending grid members substantially coextensive with the cathode and provided between said axially spaced annular discs in apertures in each of the walls of said cylinders.

DONALD HARRISON BLACK.
